UNITED STATES PATENT OFFICE

HERMAN L. BETZLER, OF WILKES-BARRE, PENNSYLVANIA

SPLIT SHED MOTION FOR LOOMS

Application filed April 21, 1930. Serial No. 446,032.

10 The present invention relates to split shed motions for looms, and comprehends means whereby the operation and control of the loom harness is regulated in a manner to provide a better, more even and tightly woven fabric.

In carrying out my invention I contemplate accelerating the movements of some harness frames with relation to others, and at predetermined intervals during the course of 10 their travel, thereby effectively separating the ends of the warp threads with a brushing effect, freeing the same of lint and the like, and also preventing floats and end breaking the warp threads.

15 The chief characteristic of the present invention resides in the regulation and control of the loom harness for the above mentioned purposes, incident to each operation of the lay.

20 Again, the invention is primarily in the nature of a loom attachment, in that it can be incorporated in any well known type of loom without requiring any alterations of the latter.

25 The nature and advantages of the invention will be better understood when the following detail description is read in connection with the accompanying drawing, the invention residing in the construction, combination and arrangement of parts as claimed.

In the drawing forming part of this application like numerals of reference indicate similar parts in the several views and wherein:

35 Figure 1 is a view in elevation and partly in section illustrating the application of the invention.

Figure 2 is a fragmentary diagrammatic view showing how the invention is connected

40 with the lay sword.

Figure 3 is a fragmentary detail view of the connection between the reciprocating rod and the turn buckles of the attachment.

Referring to the drawing in detail 10 and 45 11 respectively indicate the harness frames

which are supported by cables 12 and 13 trained over suitable guide pulleys 14 supported by the arch or frame of the loom herein indicated at 15. The cables 12 and 13 respectively are connected with the jacks 16 and 17 respectively of ordinary construction and these jacks are operated in the usual well known manner. The lay is indicated at 18, while the lay sword is indicated at 19, the latter being actuated in the ordinary well known manner. The construction thus far described is well known, and does not form any part of the present invention, the latter as above stated residing in the provision of a novel construction of means to regulate and control the movements of the harness frames, in a manner whereby some of the frames are accelerated and others retarded during their course of travel, and incident to each operation of the latter.

While the cables 12 and 13 may be connected with the jacks 16 and 17 in any suitable manner, I preferably form each cable with a loop received by an eye 20 formed on one end of a link 21. There is a link for each cable, and each link is connected with its respective jack by a substantially U-shaped member 22.

The present invention contemplates a connection between the cables 12 and 13 and the lay sword 19, so that upon each operation of the lay sword, those harness frames moving in an upward direction are accelerated, while those moving in a downward direction are retarded at a time when the harness frames are changing their relative positions, thereby effectively separating the ends of the warp threads with a brushing effect, with a view of freeing the same of lint, sticker lugs and the like, and also prevent floats and end breaking of the warp threads.

Furthermore the regulation and control of the harness frames in this manner produces far better results in that the loom produces a better, and a more even and tightly woven piece of 85 90

fabric. Manifestly the invention provides for a harness motion actuated or controlled from the lay sword, in addition to the regular motion the harness frames receive from 5 the head or jacks of the loom.

While various means may be employed to attain the desired results in the manner above specified, I have illustrated a specific embodiment of the invention which embodies an 10 operating rod 22' suspended from the corresponding ends of the turn buckles 23 which are connected with the links 21 above mentioned. As clearly illustrated in Figure 3 the corresponding lower ends of the turn buckles terminate to provide spaced eyes 24 which receive therebetween a link 25 which provides a connection between the turn buckles and operating rod 22'. A bolt 27 is passed through the eyes 24 and also through the link 15 thereby providing a pivotal joint between the turn buckles and the operating rod 22'. Suspended from the lower end of the operating 20 rod is a chain or other flexible element 28 which is trained over a suitable guide pulley 29 carried by a stub shaft 30; and this shaft is preferably journaled in a bracket 31 secured to an appropriate part of the frame 15 as illustrated. The free end of the chain 25 or flexible element 28 carries a clamp 30' of 30 any suitable construction designed to embrace the lay sword 19 so that when the lay sword is operated in the usual well known manner, a pull is exerted upon the rod 22', which in turn acts upon the cables 12 and 13 in a manner to accelerate the motion of the 35 harness frames moving in an upwardly direction, and at the same time retard the movement of the harness frames moving in a downward direction. In view of the fact 40 that this motion of the harness frames is regulated or controlled from the lay sword, it is manifest that the additional motion imparted to the harness frames takes place at a time when the harness frames are about to 45 change their relative positions during their usual course of travel, and from the motion they receive from the head or jacks of the loom. The turn buckles can be adjusted to 50 vary or regulate the degree of motion imparted to the harness frames incident to the operation of the lay sword, or it is obvious that the clamp 30' can be adjusted longitudinally of the lay sword and clamped thereto at any desired point in its length for this 55 purpose.

It is of course to be understood that the invention broadly contemplates the provision of a suitable means for regulating and controlling the variation of the harness frames 60 incident to the operation of the lay swords for the purposes specified, and that while I have illustrated and described one specific embodiment of the invention I do not limit myself to what is herein illustrated, and desire to have it understood that such changes 65

may be resorted to as fall within the scope of what is claimed.

It will be further observed that the invention is of such character that it can be incorporated in well known looms in present 70 day use, without making any alterations in the latter necessary, and will materially increase the efficiency of the loom, giving comparatively far better results and at the same time minimize the work and labor of those 75 operating the loom.

What is claimed is:

1. A harness motion for looms including means for differentiating the relative speeds of the harness frames during their usual 80 course of travel by operation of the lay.
2. In a loom, a lay, a harness motion including oppositely movable harness frames, means for operating said frames, and means operated by said lay for changing the relative 85 speeds of said frames during their usual course of travel.
3. In a loom, a lay, a harness motion including oppositely movable harness frames, means for operating said frames, and means 90 controlled by the movements of the lay for accelerating the movement of one frame with relation to the movement of the other frame at a predetermined interval during their 95 usual course of travel.
4. In a loom, a lay, a harness motion including oppositely movable harness frames, means for operating said frames, and means connected with the first mentioned means and actuated by said lay to accelerate the movement of one frame with relation to the movement of the other during a predetermined interval during their usual course of travel. 100
5. In a loom, a lay, a harness motion including oppositely movable harness frames, 105 jacks, means connecting the jacks with said frames, and means included in said connection and actuated by said lay to shorten the distance between said frames and jacks, and thereby vary the relative speeds of the frames, 110 at a predetermined interval during their usual course of travel.
6. In a loom, a lay, a harness motion including oppositely movable harness frames, means for operating said frames, means connecting the first mentioned means with said lay for differentiating the relative speeds of 115 said frames during their usual course of travel, upon each operation of the lay, and means whereby said connecting means can be 120 adjusted to vary and regulate the relative speeds of said frames incident to the operation of the lay.
7. The combination with a loom, including oppositely movable harness frames, 125 means for operating said frames, and a lay, of an attachment comprising means providing a connection between the first mentioned means and said lay for accelerating the movement of one frame with relation to the other 130

15 during their usual course of travel upon each operation of the lay.

8. The combination with a loom, including oppositely movable harness frames, 5 means for operating said frames, and a lay, of an attachment including an element connecting the first mentioned means with the lay and operable with each operation of the lay to exert a pull on said means, and thereby 10 vary the relative speeds of the harness frames at a predetermined interval during their usual course of travel.

In testimony whereof I affix my signature.

HERMAN L. BETZLER.
